UNITED STATES PATENT OFFICE.

CHARLES J. MASSINGER, OF COLLINGSWOOD, NEW JERSEY.

AUDIPHONE.

SPECIFICATION forming part of Letters Patent No. 763,414, dated June 28, 1904.

Application filed June 30, 1903. Renewed June 1, 1904. Serial No. 210,679. (No model.)

To all whom it may concern:

Be it known that I, CHARLES J. MASSINGER, a citizen of the United States, residing at Collingswood, county of Camden, and State of New Jersey, have invented a certain new and useful Improvement in Audiphones, of which the following is a specification.

My invention relates to a new and useful improvement in audiphones, and has for its object to provide a simple device to be placed in the ear-passage, so as to be invisible, to facilitate the hearing on the part of those afflicted with partial deafness; and a further object of this invention is to so construct the device that no solid portion will come in contact with the walls of the ear-passage and proper ventilation will be allowed at all times. Further objects will be obvious from the description.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is an enlarged longitudinal section through my improved audiphone; Fig. 2, a section on the line 22 of Fig. 1; Fig. 3, a rear view of the device; Fig. 4, an elevation of the device for inserting the audiphone in the ear.

Fig. 5 illustrates my improved device in position in the ear-passage.

I am aware that numerous devices have been patented which are designed to be inserted in the ear-passage to facilitate the hearing; but the purpose of my device is to intensify and increase sound-waves by a vibratory wire coil, then transfer these sound-waves to a double diaphragm, which diaphragm is close to the ear-drum and nerves of hearing.

A represents the main shell or body, which is a cylinder composed of celluloid or other suitable material, and on the outside of the cylinder are arranged rings, of felt, rubber, or other pliable soft material, which are designed to hold the device equidistant from the walls

of the ear-passage and prevent the solid portion of the device from coming in contact at any place with the walls of the ear, and the pliable rings B will give as the device is inserted.

Represents celluloid rings surrounding the cylinder A and in close contact with one side of the pliable rings B. These metallic rings C aid in holding the pliable rings B in place.

D is a rounded cap, of celluloid or other suitable material, placed over the forward end of the cylinder A.

E is a diaphragm, of mica, secured in the forward end of the cylinder A. The central portion of this diaphragm is solid, but the outer portion is slotted or cut away at the points E', so as to allow for the free circulation of air through the device. F is a second diaphragm, of mica, of about the same diameter as the solid portion of the diaphragm E. This diaphragm F is secured to the diaphragm E by a ring of rubber G, thus making an air-tight closure from which the air has been partially drawn to create a partial vacuum.

H is a metal diaphragm located near the rearward end of the cylinder A. I is a steel wire extending from this diaphragm or disk H in a straight line to the diaphragm F, where it contacts the diaphragm F lightly and then is bent back upon itself and coiled in any number of convolutions desired, the last coils being made large enough to contact the interior of the cylinder, so as to hold the wire in position.

The walls of the cylinder A and cap D are perforated to allow for ventilation and also to allow the sound-waves to pass through to the auditory nerves.

In operation the device is designed to be inserted in the ear-passage by means of a handle J, as shown in Fig. 4, the extensions J' passing inside of the cylinder and the rear end of the cylinder coming in contact with the shoulders J². After the device is inserted any sound-waves coming in contact with the disk H will be transferred to the steel wire I and intensified and increased by the vibrations of said wire, so that the sound-waves will impinge upon the diaphragm F and through the vacuum between the two diaphragms to the

diaphragm E, thus increasing and intensifying the sound to such an extent as to enable the defective ear-drum in transferring the sound to the auditory nerves.

5 The device may be removed by means of a string tied to the rearward end thereof, as shown at K in Fig. 1, or the device could be moved and inserted, if desired, by means of a pair of tweezers.

10 Of course I do not wish to be limited to the exact construction here shown, as slight modifications could be made without departing from the spirit of my invention.

Having thus fully described my invention, 15 what I claim as new and useful is—

1. In an audiphone, a perforated cylinder, rings of pliable material secured around the outside of the cylinder, a perforated cap secured over the inner end of the cylinder, a 20 diaphragm located upon the inner end of the cylinder, a coil of wire contacting the diaphragm upon its inner end, a metallic disk secured to the outer end of the wire forming the coil, as and for the purpose specified.

2. In an audiphone, a perforated cylinder of celluloid or the like, rings of felt or similar material secured around the outside of the cylinder, a perforated hemispherical cap of celluloid or like material secured upon the inner 30 end of the cylinder, a diaphragm of mica secured upon the inner end of the cylinder, the central portion of said diaphragm being solid, said diaphragm being provided with openings around its outer edge, a coil of steel wire located within the cylinder, the inner end of the coil contacting the diaphragm, a metallic disk secured to the outer terminal of the coil and arranged centrally of the cylinder, as and for 35 the purpose specified.

3. In an audiphone, a perforated cylinder of celluloid or like material, rings of pliable material secured around the outside of the cylinder and adapted to come in contact with the ear-passage, a perforated hemispherical cap 40 of celluloid or like material secured at the in-

ner end of the cylinder, a double diaphragm secured at the inner end of the cylinder, one diaphragm being held at a distance from the other, the air being partially withdrawn from the space between the two diaphragms so as 50 to form a partial vacuum, a coil of steel wire contacting the diaphragm at its inner end, a metallic disk arranged in the center of the cylinder and secured to the outer terminal of the coil, as and for the purpose specified. 55

4. An audiphone adapted to be inserted in the ear-passage so as to be invisible, consisting of a perforated cylinder, rings of pliable material surrounding said cylinder adapted to come in contact with the ear-passage, a hemispherical perforated cap secured around the inner end of the cylinder, a diaphragm of mica secured upon the inner end of the cylinder, the central portion of said diaphragm being solid and the outer portion being provided 60 with openings, a second diaphragm of mica located a slight distance outside of the first diaphragm and opposite the solid portion, a ring of rubber interposed between the two diaphragms so as to form an air-tight inclosure, 65 the air being partially withdrawn from said air-tight inclosure to form a partial vacuum, a coil of steel wire arranged within the cylinder, a metallic disk secured to the outer terminal of said wire, the wire extending in a 70 straight line inward from the disk to the diaphragm with which it contacts, then being bent back upon itself in several convolutions, the outer coils contacting the walls of the cylinder to hold the wire and disk central, means 75 for inserting and withdrawing the device from the ear-passage, as and for the purpose specified.

In testimony whereof I have hereunto affixed my signature in the presence of two sub- 80 scribing witnesses.

CHARLES J. MASSINGER.
